UNITED STATES PATENT OFFICE

161,248

GAME BOARD

Edwin Eugene Darr, Garden City, N. Y.

Application March 17, 1948, Serial No. 145,189

Term of patent 14 years

(Cl. D34—5)

To the Commissioner of Patents:

Be it known that I, Edwin Eugene Darr, a citizen of the United States of America, residing at Garden City, Long Island, in the county of Nassau and State of New York, have invented a new, original and ornamental Design for a Game Board, of which the following is a specification, reference being had to the accompanying drawing forming a part thereof.

In said drawing:

Fig. 1 is a perspective view of the game board, showing my new design, and

Fig. 2 is a vertical sectional view thereof taken on line 2—2 of Fig. 1.

The dominant features of my design are shown in solid lines in the drawing.

I claim:

The ornamental design for a game board, as shown and described.

EDWIN EUGENE DARR.
